HAND GRENADE

George Keeling, Ithaca, N. Y.

Application October 7, 1941, Serial No. 414,017

2 Claims. (Cl. 102—64)

The present invention relates to new and useful improvements in hand grenades, and has for its primary object to provide, in a manner as hereinafter set forth, a device of this character comprising an impact firing mechanism of a novel construction and arrangement whereby the grenade will be caused to explode instantly upon striking an object or surface.

Another very important object of the invention is to provide a hand grenade of the aforementioned character comprising means for positively preventing firing until the grenade is to be used.

Other objects of the invention are to provide a hand grenade of the character described which will be comparatively simple in construction, compact, light in weight, reliable and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a vertical sectional view through a hand grenade constructed in accordance with the present invention.

Figure 2 is a view in horizontal section, taken substantially on the line 2—2 of Figure 1.

Figure 3 is a detail view in bottom plan of the slidable fulminate or detonating medium.

Figure 4 is a bottom plan view of the grenade.

Figure 5 is a vertical sectional view, showing the grenade ready to be thrown.

Figure 6 is a detail view in perspective of the fulminate chamber.

Referring now to the drawings in detail, it will be seen that the embodiment of the invention which has been illustrated comprises a substantially spherical grooved shell 1 of suitable metal. The shell 1 is for the reception of an explosive charge 2. Toward this end, the shell 1 has threaded thereto a filling plug or closure 3.

Threadedly mounted in the shell 1 at a point diametrically opposite the closure 3 is a plug 4. The plug 4 includes a smooth or unthreaded, reduced inner portion 5 having mounted thereon a cylindrical chamber 6. The inner end of the chamber 6 is closed by a cap 7.

Slidably mounted in the cylindrical chamber 6 is a detonating medium 8. The face of the detonating medium 8 which is opposed to the plug 4 is provided with igniting caps 9. Coll

8 away from the plug 4. The cylindrical chamber 6 communicates with the shell 1 through slots 11 formed in said chamber at a point between the plug 4 and the detonating medium 8. The opposed ends of the members 4 and 8 have formed therein sockets 12 which accommodate the end portions of the coil springs 10.

Projecting from the inner end of the plug 4 is a pair of firing pins 13 for igniting the caps 9. Extending into the plug 4 from the outer end thereof is a threaded socket or bore 14. The bore 14 includes a smooth, reduced inner end portion 15 which communicates with a socket 16 in the inner end portion of the plug 4.

The bore 14 is adapted to threadedly receive a screw 17. Projecting longitudinally from the inner end of the screw 17 is a pin 18 which is slidable in the smooth reduced portion 15 of the socket or bore 14. The pin 18 terminates, at its inner end, in a head 19 which is engageable with the detonating medium 8.

It is thought that the operation of the device will be readily apparent from a consideration of the foregoing. Briefly, when the screw 17 is threaded home in the bore 14 the headed end 19 of the pin 18 is engaged with the detonating medium 8 for positively spacing said medium from the firing pins 13, as seen in Figure 1 of the drawings. A lock washer 20 is provided for the screw 17. When the grenade is to be used, the

30 screw 17 is backed out of the bore 14 (see Fig. 5) thereby disengaging the pin 18 from the detonating medium 8. Only the coil springs 10 now maintain the detonating medium 8 out of contact with the firing pins 13. The grenade is then thrown and when it strikes an object the coil springs 10 are overcome by the impact and the igniting caps 9 are caused to engage the pins 13 by which they are fired. When the detonating medium 8 is thus ignited the fire passes through the slots 11 into the shell 1 and explodes the charge 2 therein. As shown in Figure 5 of the drawings, the socket 16 accommodates the head 19 of the pin 18 when said pin is in retracted position.

45 When the head 19 seats in the socket 16 further unscrewing of the screw 17 from the plug 4 is prevented. It will thus be seen that the screw 17 cannot be lost.

It is believed that the many advantages of a 50 hand grenade constructed in accordance with the present invention will be readily understood, and although a preferred embodiment of the device is as illustrated and described, it is to be understood that changes in the details of construction and in the combination and arrangement

of parts may be resorted to which will fall within the scope of the invention as claimed.

What is claimed is:

1. A hand grenade comprising a shell for the reception of an explosive, a plug threadedly mounted in said shell, a substantially cylindrical chamber mounted in the shell on the plug and having openings therein communicating with said shell, a pair of firing pins on the plug, a detonating medium slidably in the chamber and engageable with the firing pins, resilient means yieldingly holding the detonating medium out of contact with the firing pins, and means on the plug for positively spacing the detonating medium from the firing pins, the last-named means including a screw threadedly mounted in the plug, and a pin on said screw extending into the chamber and engaged with the detonating medium.
2. A hand grenade comprising a shell for the

reception of an explosive, a plug threadedly mounted in said shell, a substantially cylindrical chamber mounted in the shell on the plug and having openings therein communicating with said shell, a pair of firing pins on the plug, a detonating medium slidably in the chamber and engageable with said pins, a screw threaded into the plug from the outer end thereof, a pin on the inner end of the screw extending into the chamber, a head on the inner end of the second-named pin engageable with the detonating medium for positively spacing said medium from the firing pins, coil springs mounted between the plug and the detonating medium for yieldingly holding said medium away from the firing pins when the screw is retracted, and a filler closure in the casing.

GEORGE KEELING.
